UNITED STATES PATENT OFFICE

WILLIAM G. KEITH AND JOSEPH A. MANARIK, OF CHICAGO, ILLINOIS, ASSIGNORS TO
WELSBACK TRAFFIC SIGNAL COMPANY, OF PHILADELPHIA, PENNSYLVANIA, A
CORPORATION OF DELAWARE

DESIGN FOR A TRAFFIC LIGHT DEVICE

Application filed February 19, 1932. Serial No. 42,941. Term of patent 14 years.

To all whom it may concern:

Be it known that we, WILLIAM G. KEITH and JOSEPH A. MANARIK, citizens of the United States, both residing at Chicago, in the county of Cook and State of Illinois, have invented a new, original, and ornamental Design for a Traffic Light Device, of which the following is a specification, reference being had to the accompanying drawing, forming a part thereof.

Figure 1 is a front elevational view of a traffic light device unit embodying our new

design comprising an upright supporting post having an enlarged reflecting member adjacent the upper end thereof held in a position at one side of the supporting post by ornamental brackets; and

Fig. 2 is a fragmentary side elevational view of Figure 1.

We claim:

The ornamental design for a traffic light device substantially as shown and described.

WILLIAM G. KEITH.
JOSEPH A. MANARIK.
